UNITED STATES PATENT OFFICE.

ORIN J. BEMISS, OF YPSILANTI, MICHIGAN.

SIGNALING DEVICE FOR AUTOMOBILES.

1,167,372.

Specification of Letters Patent.

Patented Jan. 11, 1916.

Application filed January 9, 1915. Serial No. 1,381.

To all whom it may concern:

Be it known that I, ORIN J. BEMISS, a citizen of the United States, residing at Ypsilanti, in the county of Washtenaw, State of Michigan, have invented certain new and useful Improvements in Signaling Devices for Automobiles; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to signaling devices especially designed and adapted for use on automobiles, and consists in the construction and arrangement of parts as hereinafter fully set forth and claimed.

The invention has for its object the provision of a simple and efficient signaling device adapted for attachment to an automobile and to be manually operated by the driver thereof, whereby a rear signal may be displayed at the will of the operator to indicate any contemplated change in the speed or course of the vehicle to be made, so as to notify and forewarn an approaching or following vehicle of such intention and enable the driver thereof to so govern or direct his course as to avoid confusion or interference and a possible collision, which might otherwise occur, with the result of serious injury to both vehicle and occupants.

The invention contemplates such a construction of the device by which the above object is attained as will provide a suitable support or housing for attachment to the rear of an automobile and for containing the signaling mechanism, to which actuating means is connected, which extends to the foot board within easy access for control by the foot of the operator. The arrangement is such as to provide a selective control for the signaling means, in the operation of which a signal indicating a reduction of speed may be displayed independently, or a change in the course of the vehicle to either a right or left hand direction may be indicated simultaneously with the display of the signal indicating the change in speed.

The preferred form of embodiment of the novel features of the present invention is

illustrated in the accompanying drawings, 55 in which:

Figure 1 is a sectional elevation of a portion of an automobile frame and body, showing the signaling device and actuating means attached thereto in position for operation. Fig. 2 is a plan view of a portion of the foot board, showing a T-shaped way therein for permitting a selective movement of the foot lever for actuating the signaling mechanism. Figs. 3, 4 and 5 are diagrammatic views of the exposed face of the signal housing; Fig. 3 showing the sign plate inscribed "slow down" displayed to indicate a change of speed; Fig. 4 showing the sign plate displayed in connection with a signal hand indicating a turn or change of course to the left, and Fig. 5 showing the sign plate and signal hand indicating a turn to the right. Fig. 6 is a view looking into the housing with the front plate removed, showing the mechanism in elevation with the connecting studs in section, and indicating by dotted lines an actuated position of the sign plate and one of the signal hands. Fig. 7 is a central vertical section through the housing and parts, taken on dotted lines 7-7 of Fig. 6, the parts being in their normal position. Fig. 8 is a transverse zig-zag sectional view through the parts on dotted line 8-8 of Fig. 6. Fig. 9 is a fragmentary sectional view taken on dotted line 9-9 of Fig. 6.

Referring to the drawings by the characters of reference marked thereon, 1 represents the back or supporting plate of the housing, within which the signaling mechanism is mounted, and which is shown as having a right angled bent portion 2 secured to the back of an automobile body 3, by bolts or screws 4, as shown in Figs. 1 and 7, but which may be attached or supported in any other suitable manner.

A face plate 5 constituting the outer wall or cover for the housing is spaced apart from and supported upon the back plate 1 by means of four screw studs 6 which also serve as supports for certain parts of the signaling mechanism. Said studs extending through the face plate 5 are anchored in the back plate 1 by jam nuts 7 at their threaded ends, and are each provided with a pair of spacing sleeves 8 and 9 for positioning the parts thereon. Mounted to slide

vertically upon two of the studs 6 is a T-shaped sign plate 10 having elongated apertures 11 formed in the body thereof, through each of which a stud 6 passes and between 5 the spacing sleeves 8 and 9 of which the body of the plate is interposed and guided thereby in its vertical movement. (See Figs. 6 and 7). The upper end of the sign plate normally lies in a plane below the upper end 10 of the face plate 5 of the housing, and may have inscribed upon its outer face suitable characters to indicate a change of speed, such as "slow down," as shown, and which will be exposed to view when said sign plate 15 is projected from within the housing, as shown in Fig. 3, and indicated by dotted lines in Fig. 6.

A pair of signaling members in the form of hands 12 are disposed upon opposite sides 20 of the body of the sign plate in reversely opposed relation to each other, each being pivoted at its lower end upon a stud 6 and so positioned between the spacing sleeves 8 and 9 thereon as to clear said sign plate in lying 25 in their normal vertical positions within the housing, from which they are adapted to swing respectively in right and left hand directions to oppositely extended and substantially horizontal positions therewith, as 30 shown in Figs. 4 and 5 and indicated by dotted lines in Fig. 6. Each of said signal hands is operatively connected with one side of the sign plate by means of a strap link 13, the lower end of which is pivoted to the 35 lower end of the hand, eccentric to the pivot of said hand, by a screw stud 14 which passes through said hand and is threaded through said link, being anchored therein by a jam nut 15. The upper end of each 40 link is provided with a slot 16 which receives a screw stud 17 anchored at its head in said sign plate and receiving on its threaded end a washer 18 and jam nut 19 to slidably retain said strap in engagement therewith. By this arrangement the parts are so 45 connected as to permit of the vertical movement of the sign plate independently of the signal hands, while an outward swinging movement of either of the hands will impart 50 an upward vertical movement to said sign plate simultaneously therewith, and through the downward movement of said plate movement will be imparted to return said hands to their normal vertical position within the 55 housing. To provide means for retaining said hands in their normal position against an accidental outward movement when said sign plate is raised independently, an upturned tongue 20 is formed at the inner edge 60 of each hand which is adapted to engage with a correspondingly upturned flange 21 formed on opposite edges of the body portion of said sign plate, as indicated by dotted lines in Fig. 6, and more clearly 65 shown in Figs. 7 and 9.

Motion is imparted to operate the hands in conjunction with the sign plate and independently of each other in opposite directions, by means of a crank yoke 22, having a centrally projecting hub 23 journaled to 70 rock in a bearing hanger 24, which is secured by bolts 25 to the frame of the car in central vertical alinement with the signal housing, and with the crank arms 27 of the yoke extending rearward relatively in a 75 horizontal plane. The outer end of each of said crank arms is provided with a threaded stem 27' upon which the lower end of a connecting link 28 is pivotally received and secured by a jam nut 29, and the upper end of 80 each of these links is pivotally and slidably connected to the lower end of a corresponding signal hand at a point eccentric to the pivot of said hand and opposite its pivotal connection with the link 13, through the 85 medium of a stud 30 which passes through a slot 31 in said hand and through a spacing washer 32 into said link, being locked therein by a jam nut 33. (See Figs. 6 and 8.) The studs 30 of the connecting links normally lie in engagement with the lower ends 90 of the slots 31 of the hands, and the angle of said slots, with relation to the direction of movement imparted to the links through the rocking of the crank yoke 22, is such as to 95 render the links operative for transmitting movement to the hands in a downward direction only, the upward movement of the link being accommodated by the travel of the stud in the slot of the hand. 100

Movement is imparted to the crank yoke through a rock shaft 34 journaled in a bearing hanger 35 secured to a frame 26 of the car and provided at its forward end with an upwardly extended foot control arm 36, 105 which is secured thereon by jam nuts 37, and, extending through a T-shaped aperture 38 in the foot board 39 of the car, is adapted to be shifted therein to impart either a longitudinal or rocking movement to said shaft. 110 The rear end of said shaft extends through and is supported in the hub 23 of the crank yoke in which it is splined by means of flattened surfaces 40 formed on said shaft and engaged by a correspondingly shaped aperture in said hub, so as to effect a driving engagement and permit of the longitudinal movement of said shaft therein. (See Figs. 1 and 7.) 115

The longitudinal movement of the rock shaft is transmitted to impart a vertical movement to the sign plate through a bell crank lever 41 having a connecting rod 42 pivoted thereto at one end within the bifurcated end of said lever upon a stud 43 passing therethrough and secured by a jam nut 44, and pivotally connected at its upper end to the lower end of said sign plate between ears 45 thereon through which a stud 46 is passed and secured by a jam nut 47. The 120 125 130

fulcrum end of said bell crank lever is forked and pivoted astride the end of a fixed arm 48 extending from the bearing hanger 24 upon a stud 49 secured therein by a jam nut 50, and the free ends of said fork extending upon opposite sides of the shaft 34 are provided with circular bearing terminals 51 engaged upon one side by a nut or shoulder 52 on the end of the shaft, and upon the opposite side by a collar 53 loosely mounted on said shaft and yieldably held in contact with said terminals by a coiled spring 54 embracing said shaft and interposed between said collar and the inner face of the crank yoke 22, as clearly shown in Fig. 7. By this arrangement the tension of the coiled spring is exerted axially upon the rock shaft and outwardly upon the engaged end of the bell crank, and through said bell crank and its connecting rod a downward tension is exerted upon the sign plate, which in turn imparts an inward swinging tension to the signal hands through the engagement of the studs of said sign plate with the lower ends of the slots of the links connecting said hands therewith, whereby said plate and hands are normally retained in contracted position within the housing. By this arrangement it will be seen that pressure applied in a forward direction to the foot control arm will move the shaft longitudinally against the tension of the spring and rock the bell crank, through which an upward movement will be imparted to the sign plate to project and display the characters thereon above the housing, as shown in Fig. 3, in which position the studs 17 of the sign plate will have traveled upwardly in the slots of the connecting links 13, and the tongues 20 of the hands will be engaged by the flanges 21 of said sign plate to retain said hands against an outward swinging movement, thus displaying the sign plate only to indicate the intention to slow down. When desirous of indicating an intention to turn to the right the foot control arm is swung in a corresponding direction to rock the shaft and crank yoke which in its downward movement upon one side will impart through its connecting link an outward swinging movement to the corresponding signal hand, and through the link connecting said hand with the sign plate an upward movement will be transmitted to said plate to display said hand and plate simultaneously and indicate the change both in speed and direction to be made, as shown in Fig. 5. It will be apparent that a movement of the foot control lever to the left will effect the operation of the sign plate and hand in a corresponding direction, as shown in Fig. 4, in identically the same manner as described for the right hand operation, and that upon releasing the pressure upon the foot control arm the tension of the coiled spring acting upon the

shaft and bell crank will restore the parts to their normal positions.

Having thus fully set forth my invention, what I claim as new, and desire to secure by Letters Patent, is:

1. A signaling device comprising a housing, a sign plate movably mounted in said housing, a signaling arm pivoted to swing into and out of said housing and operatively connected with said sign plate to impart movement thereto in one direction with the movement of said arm, and an operating member having actuating means connected to said sign plate and to said signaling arm movable in one direction for imparting movement to said sign plate and movable in another direction for imparting movement to said arm and to said sign plate.

2. A signaling device comprising a housing, a sign plate movably mounted in said housing, a signaling arm pivoted to swing into and out of said housing, a connecting member carried by said arm and engaged with said sign plate to impart movement thereto in one direction through the movement of said arm, an operating member movable in different directions and carrying actuating means connected to said sign plate and to said signaling arm, operative in one direction for imparting movement to said sign plate and actuatable in another direction for transmitting movement to said signaling arm and to said sign plate.

3. A signaling device comprising a housing, a sign plate mounted to slide vertically in said housing, a signaling arm pivoted in said housing to swing therefrom, a connecting member pivoted to said signaling arm and slidably engaged with said sign plate for imparting movement thereto in one direction, an operating member movable in different directions having a control arm for differentiating the movement thereof, and actuating means connecting said operating member with said sign plate and said signaling arm, whereby through the movement of said control arm in one direction movement is imparted to raise said sign plate and by movement in another direction said plate is raised through the outward swinging motion transmitted to said signaling arm.

4. In a signaling device, a supporting frame, a housing mounted thereon, a sign plate mounted to slide vertically in said housing, a signaling arm pivoted in said housing to swing therefrom, a connecting link pivoted to said signaling arm and slidably connected to said sign plate to impart movement to and permit said plate to move independently thereof in one direction, an operating member mounted on said frame and movable thereon in different directions, a crank arm on said operating member having a linked connection with said signaling

- arm for transmitting movement thereto through the movement of said operating member, and a lever pivotally supported on said frame in engagement at one end with said operating member and having a linked connection at its opposite end with said sign plate for imparting movement thereto through the movement of said operating member in one direction.
19. 5. In a signaling device, a supporting frame, a housing mounted thereon, a sign plate mounted to slide vertically in said housing, a signaling arm pivoted to swing therefrom, a connecting link pivoted to said arm and slidably engaged with said sign plate, an operating shaft journaled to rock and to slide longitudinally in bearings on said frame and having a control arm for differentiating the movement of said shaft, a crank arm splined on said shaft to rock therewith and permit longitudinal movement of said shaft therein, a link pivotally connected to said crank arm and to said signaling arm for transmitting the rocking movement of said shaft to swing said arm and raise said plate, a lever pivotally supported on said frame in sliding contact at one end with said shaft and having a link pivotally connected thereto and to said sign plate for transmitting the longitudinal movement of said shaft to raise said plate, and a coiled spring interposed between said lever and said crank for returning said parts to their normal positions.
6. In a signaling device, a supporting frame, a housing mounted therein, a sign plate mounted to slide vertically in said housing, a signaling arm pivoted to swing therefrom, a connecting link pivoted to said arm and slidably engaged with said sign plate, an operating shaft journaled to rock and to slide longitudinally in bearings on said frame and having a control arm for differentiating the movement of said shaft, a crank arm splined on said shaft to rock therewith and permit longitudinal movement of said shaft therein, a link operatively connecting said crank arm with said sign arm for imparting movement in one direction to swing said arm, and inoperative to impart movement thereto in the opposite direction, a lever pivotally supported on said frame in movable engagement with said shaft at one end and having a link pivotally connecting its opposite end to said sign plate to raise said plate through the longitudinal movement of said shaft, a collar embracing said shaft and engaging said lever, and a coiled spring confined between said collar and said crank for exerting tension on said shaft and lever.

In testimony whereof, I sign this specification in the presence of two witnesses.
